US0D1110403S

(12) **United States Design Patent** (10) **Patent No.:** **US D1,110,403 S**
(45) **Date of Patent:** **** Jan. 27, 2026**

(54) **STAMP**

(71) Applicant: **Trodat GmbH**, Wels (AT)

(72) Inventor: **Manfred Ortner**, Pennewang (AT)

(73) Assignee: **Trodat GmbH**, Wels (AT)

(**) Term: **15 Years**

(21) Appl. No.: **29/966,695**

(22) Filed: **Oct. 4, 2024**

(30) **Foreign Application Priority Data**

Apr. 8, 2024 (EM) 015056811-0002

(51) **LOC (15) Cl.** **18-99**

(52) **U.S. Cl.**

USPC **D18/15**

(57) **CLAIM**

The ornamental design for a stamp as shown and described.

DESCRIPTION

FIG. 1 is a top side perspective view of a stamp;

FIG. 2 is a front side elevational view thereof;

FIG. 3 is a left side elevational view thereof;

FIG. 4 is a rear side elevational view thereof;

FIG. 5 is a right side elevational view thereof;

FIG. 6 is a top side elevational view thereof; and,

FIG. 7 is a bottom side elevational view thereof.

The broken line showings in the bottom side elevational view of the stamp in FIG. 7 are included for the purpose of illustrating environmental structure and form no part of the claimed design.

1 Claim, 7 Drawing Sheets
